UNITED STATES PATENT OFFICE

FELIX BOUDOU, OF PARIS, FRANCE

DESIGN FOR A HEATING DEVICE FOR CURLING IRONS

Application filed December 17, 1931, Serial No. 42,162, and in France November 24, 1931. Term of patent 7 years.

To all whom it may concern:

Be it known that I, FELIX BOUDOU, a citizen of the Republic of France, residing in Paris, France, have invented a new, original, and ornamental Design for a Heating Device for Curling Irons, of which the following is a specification, reference being had to the accompanying drawing, forming part thereof.

In the drawing, Fig. 1 is a perspective view of a heating device for curling irons, showing my new design; and

Fig. 2 is an edge view thereof.

I claim:

The ornamental design for a heating device for curling irons, as shown.

FELIX BOUDOU.
